(57) **CLAIM**

The ornamental design for a toy projectile launcher, as shown and described.

DESCRIPTION

FIG. 1 is a perspective view of a toy projectile launcher, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevation view thereof; and,

FIG. 7 is a right side elevation view thereof.

The broken lines in the figures illustrate portions of the toy projectile launcher that form no part of the claimed design.

1 Claim, 5 Drawing Sheets
